BAND ANTENNA

Pierre Paul Gamet, Paris, France; vested in the
Alien Property CustodianApplication March 27, 1942, Serial No. 436,535
In France March 28, 1941

10 Claims. (Cl. 250—33)

The present invention relates to improvements in multiple strand aerials, and aerials comprising a shaped flat conducting band, particularly for very high frequencies.

The invention relates more particularly to aerials or aerial systems having a high efficiency and a large aperiodicity, for the transmission or the reception of radio waves; it is applicable both to receiving and to transmitting aerials and it relates more particularly to the aerials which are used for short and very short waves.

With aerials of this type heretofore used, experience shows that one can rely on a certain aperiodicity characteristic only when the energizing of the said aerials is effected under the best conditions of coupling and of matching of impedance with the transmission line, which makes it necessary to modify the matching circuits when working with a number of different wave lengths.

On the other hand, aerials are generally located at inaccessible places for instance on the top of a mast or of a building and, in any case, one encounters great difficulties in changing the aerial structure or the transmission line once they are set up. However, it is most desirable to be able to use such a unit in a predetermined range of wave lengths, the aerial retaining in the said range the same properties of radiation and the same characteristic features from the point of view of the transmission or receiving apparatus with which it is coupled.

The present invention offers this latter advantage without making it necessary, in any way, to modify the mechanical and electrical characteristics of the aerial and of the matching circuit once they are set up and mounted, the said aerial being designed so as to obtain a large aperiodicity, the output radiated by this aerial remaining constant over a large range of wave lengths, and its optimum operation being such that it does not require an energizing circuit specially designed to have the best conditions of coupling and of matching of impedance.

My improved aerial permitting to attain the above mentioned objects presents the characteristic features which will appear from the following description and more particularly from the appended claims.

Aerials according to the invention are shown by way of examples in the accompanying drawings, in which:

Figure 1 is a general perspective view of the aerial from the front.

Figure 2 is a top plan view of the aerial.

Figure 3 shows a detail of the top terminal loop.

Figure 4 shows the developed surface of the terminal loop on a plane.

Figure 5 is a diagram of the elementary aerial element of which the complete aerial may be considered to be composed.

The aerial is formed of a flat conducting band 1, a second flat conducting band 2 parallel to band 1, and a flat conducting band 3 parallel to band 2 and in line with band 1; these bands 1 and 3, on the one hand, and 2, on the other hand, are spaced from each other by a distance which is small with respect to the radiated or received wave length.

The extremities 4 of band 1, and 5 of band 3, are bent for instance at a right angle at 6 and 7, and carry terminals 8 and 9 for securing both wires of the transmission line or the connection wires of the coupling means.

The bands 1 and 2, on the one hand, and 3 and 2, on the other hand, are connected together at their ends by a terminal band 10 and by a terminal band 11 respectively, which are bent in the form of a loop which is such that when developed or spread out on a plane it forms a parabolic surface.

The electrical constants of the aerial depend upon the following dimensions:

30 The tip-to-tip distance at the rear of the structure shown in Fig. 1, L^1 the length of the branch 2, and of the branch 1 together with the branch 3, measured respectively on the rear edges 12, and 13—14.

35 L^2 the length of the branch 2, and also of branch 1 together with branch 3, measured on the front edges 15, 16 and 17.

O^1 the thickness distance at the rear from left to right between the edges 13 and 14, on the one hand, and 12, on the other hand, of the branches 1, 3 and 2.

O^2 the thickness distance at the front from left to right between the edges 16 or 17, on the one hand, and 15, on the other hand, of the branches 1, 3 and 2.

b the depth of the aerial from front to back.

The dimensions L^1 , L^2 , O^1 and b can vary over a considerable range according to the desired range of aperiodicity and the scale of frequencies to be transmitted or received. From this fact, the general form of the aerial can be considerably modified according to the choice of the preceding dimensions.

An aerial of the described type possesses a comparatively low impedance; it is necessary to en-

ergize it through a conventional matching circuit.

This aerial operates as follows:

It is comparable to an infinite number of aerials joined side by side and closely coupled together and formed (see Figure 5) of a strand 18, on the one hand, and two strands 19 and 20, on the other hand, of rectilinear form, parallel and separated from another by a distance which is small with respect to the radiated or received wave length. These strands are connected at their extremities by terminal loops 21 and 22.

The length of each of these elementary aerials varies progressively within the limits L^1 , L^2 ; the distance between each of the strands 19 and 20, on the one hand, and 18, on the other hand, varies progressively between O^1 and O^2 . Thus, the complete structure is tapered in both length and breadth in a direction perpendicular to these elementary aerials, and has substantially the shape of the frustum of a cone.

Suppose two points 23, 24 of the wires of the elementary aerial at the same height X over the lower tip point 25. The value of the currents I^1 and I^2 as a function of time is given to a first approximation by the following expression:

$$I^1 = A \sin 2\pi \left(\frac{t}{T} + \frac{X}{\lambda} \right)$$

$$I^2 = A \sin 2\pi \left(\frac{t}{T} - \frac{X}{\lambda} \right)$$

where A is a constant, T the period of the oscillations, λ the wave length and t the time.

These equations are true with the single assumption that the terminal loops do not modify the propagation of the waves, and experience confirms this fact.

One sees that both these equations are identical in their form with the single exception of the sign of the term

$$\frac{X}{\lambda}$$

From the point of view of the field produced at a great distance and since the distance between both strands is small with respect to the wave length, the radiation is identical to that of a single conductor the intensity of which would be the sum of both preceding intensities, which sum has for its expression:

$$I = I^1 + I^2 = 2A \sin 2\pi \frac{t}{T} \cos 2\pi \frac{X}{\lambda}$$

One sees that for standing waves this intensity corresponds with that of a dipole tuned to the wave length the intensity of which at the current loop is equal to twice the intensity in each branch. This calculation shows well the radiation power of this elementary aerial and experience confirms it entirely.

The aerial according to the present invention being formed of an infinite number of these elementary aerials, it has a radiation value which can be considered for a given frequency as the sum of the partial radiations of each elementary aerial while taking into account their mutual inductance.

Experience shows that the radiation resistance of this unit is nearly constant over a large range of wave lengths and that, on the other hand, its aperiodicity is obtained within wide limits even then when the energizing circuit does not correspond to the best conditions of coupling and of matching of the impedance.

The invention is generally applicable and can

be applied to all the aerials comprising systems of any antennae (radiogoniometers, radiobeacons); it is more particularly advantageous for transmitters working various different stations for transmitting aerials or receiving aerials with wide band pass characteristics, in order to obtain the minimum distortion during transmission or reception, as of the image in television.

I claim:

10. 1. A broad band antenna particularly for ultra-high frequencies, comprising a conducting band having substantially the shape of the frustum of a cone, said band being discontinuous at a region of its conical surface for the application of operating terminals to its portions adjoining said region.
15. 2. A broad band antenna particularly for ultra-high frequencies, comprising a conducting band having substantially the shape of the frustum of a cone, said band being discontinuous at a region of its conical surface for the application of operating terminals to its portions adjoining said region, the smallest dimension of the base of said cone being small with relation to the operating wave length.
20. 3. A broad band antenna particularly for ultra-high frequencies, comprising a conducting band having substantially the shape of the frustum of a cone whose base is a figure composed of two parallel lines of substantially equal length joined together at their respective ends by continuous curved lines, the distance between said parallel lines being small with relation to their length and small with relation to the operating wave length.
25. 30. 4. A broad band antenna particularly for ultra-high frequencies, comprising a conducting band having substantially the shape of the frustum of a cone whose base is a figure composed of two parallel lines of substantially equal length joined together at their respective ends by continuous curved lines, the distance between said parallel lines being small with relation to their length and small with relation to the operating wave length.
30. 45. 5. A broad band antenna particularly for ultra-high frequencies, comprising a conducting band having substantially the shape of the frustum of a cone whose base is a figure composed of two parallel lines of substantially equal length joined together at their respective ends by continuous curved lines, the distance between said parallel lines being small with relation to their length and small with relation to the operating wave length, said band being discontinuous at a region thereof for the application of operating terminals to its portions adjoining said region.
45. 50. 6. A broad band antenna particularly for ultra-high frequencies, comprising a conducting band having substantially the shape of the frustum of a cone whose base is a figure composed of two parallel lines of substantially equal length joined together at their respective ends by continuous curved lines, the distance between said parallel lines being small with relation to their length and small with relation to the operating wave length, said band being discontinuous at a region intermediate and substantially midway of a long side thereof for the application of operating terminals to its portions adjoining said region.
50. 55. 7. A broad band antenna particularly for ultra-high frequencies, comprising a conducting band shaped to form a substantially continuous closed surface having a longitudinal plane of symmetry and having a cross-section defining a plane perpendicular to said plane of symmetry and constituted of two long parallel lines of equal length connected together at their ends by continuous curves, said surface being tapered in both length and breadth perpendicular to the plane of said cross section, the distance between said parallel lines being small with relation to their length and small with relation to the operating wave length.
60. 65. 8. A broad band antenna particularly for ultra-high frequencies, comprising a conducting band shaped to form a substantially continuous closed surface having a longitudinal plane of symmetry and having a cross-section defining a plane perpendicular to said plane of symmetry and constituted of two long parallel lines of equal length connected together at their ends by continuous curves, said surface being tapered in both length and breadth perpendicular to the plane of said cross section, the distance between said parallel lines being small with relation to their length and small with relation to the operating wave length.
70. 75. 9. A broad band antenna particularly for ultra-

high frequencies, comprising a conducting band constituted of the surface generated by translating parallel to itself a closed plane figure which is long relative to its breadth, and the dimensions of said figure being at the same time continuously varied progressively in the same sense of magnitude in its successive positions as it is so translated, the distance between the long branches of said figure being small with relation to the operating wave length.

8. A broad band antenna particularly for ultra-high frequencies, comprising a conducting band constituted of the surface generated by translating parallel to itself a plane figure consisting of two long parallel lines whose ends are connected together by curves, and the dimensions of said

figure being at the same time continuously varied progressively in the same sense of magnitude in its successive positions as it is so translated, the distance between said parallel lines being small with relation to the operating wave length.

9. An antenna according to claim 8, the terminal curved surfaces connecting the long sides of said surface whose elements are parallel, being surfaces which are parabolic surfaces when de-

veloped on a plane.

10. An antenna according to claim 8, one of the long sides of said surface being discontinuous at a region thereof intermediate its length for the application of operating terminals thereto 15 to its portions adjoining said region.

PIERRE PAUL GAMET.
